UNITED STATES PATENT OFFICE.

ARTHUR W. SMITH, OF NEW YORK, N. Y., ASSIGNOR TO REMINGTON TYPEWRITER COMPANY, OF ILION, NEW YORK, A CORPORATION OF NEW YORK.

TYPE-WRITING MACHINE.

1,221,236.

Specification of Letters Patent.

Patented Apr. 3, 1917.

Application filed November 24, 1915. Serial No. 63,234.

To all whom it may concern:

Be it known that I, ARTHUR W. SMITH, citizen of the United States, and resident of the borough of Manhattan, city of New York, in the county of New York and State of New York, have invented certain new and useful Improvements in Type-Writing Machines, of which the following is a specification.

10 My present invention relates to differential or denominational side gage or stop mechanism and its main object is to provide improved mechanism of the character specified.

15 Specifically the object of my present invention is to improve the denominational side gage mechanism which forms in part the subject-matter of my prior application, Serial No. 19,871, filed April 8, 1915.

20 To the above and other ends my invention consists in the features of construction, combinations of devices and arrangements of parts hereinafter described and particularly pointed out in the claims.

25 In the accompanying drawings wherein the invention is illustrated as applied to a carriage of the No. 11 Remington front-strike typewriting machine,

Figure 1 is a fragmentary plane of said carriage embodying the invention.

Fig. 2 is a fragmentary side elevation partly in section showing the novel side gage contrivance and associate parts.

30 Figs. 3 and 4 are, respectively, face and back views of the denominational side gage contrivance.

Fig. 5 is an enlarged sectional view taken through the axis of the side gage contrivance.

40 Fig. 6 is a perspective view of parts of the side gage contrivance.

Referring to Figs. 1 and 2 the platen carriage or carrier comprises front and rear bars 1 and 2 and connecting end bars 3 and 4, said carriage supporting a rotary platen 5. Brackets 6 rigid as usual with the front bar provide bearings for the pivot rod 7 of a pressure bail which further comprises parallel arms 8 supporting a rod or shaft 9 extending parallel with the platen at its front upper side and carrying pressure rolls 10. Mounted on the pressure bail is a second rod or shaft 11, said shaft being provided at its ends with reduced portions or pintles 12

which bear in the arms 8, the second rod 11 55 being parallel with the rod 9. The right-hand arm 8 has connected to it a draw spring 13 which is anchored to the right-hand bracket 6, the pressure of the rolls 10 on the platen 5 being in part received from said 60 spring and in part from a second draw spring 14 which is at one end connected to a pin 15 on the rod, said spring extending forward under the left-hand arm 8 and being anchored to the left-hand bracket 6. 65 Said spring has several functions as will hereinafter appear.

The rod or shaft 11 provides a support for a side gage, guide or stop contrivance 16 which is adjustable as a whole along said 70 rod 11 and lengthwise of the platen. Said contrivance may be said generally to comprise a support or carrier, a side gage or stop proper mounted on said support and means controlled by a finger piece or key 75 for progressively moving said side gage proper step-by-step lengthwise of the platen independently of said support and without disturbing the location of said contrivance as a whole. Said support or carrier in the 80 present instance is in the form of a rectangular block 17 (Figs. 2-5) which is perforated to fit over and slide on the rod 11. The block or slide 17 may be fixed in adjusted 85 positions by means of a thumb screw 18 which is threaded through the block at its under side and abuts against a flat face 11^a on the rod 11. The upper face of the block 17 is preferably provided or formed with teeth 19 constituting a rack section or rack. 90

The device comprising the side gage proper is best shown in the detached view (Fig. 6). Said device numbered as a whole as 20 is preferably formed of sheet metal and comprises a disk portion 21, a trough-like portion 22 bent rearward and upward at the lower side of the disk portion 21 and adapted partly to embrace the slide 17. A side gage, guide or stop proper 23 is bent rearward at right angles from the right side of 95 the disk portion 21. It is triangular in shape and is formed at its rear with a sort of hook 24 which is adapted to fit over the top of the rod 9 and is also provided with a round hole indicated at 25 to afford a passage for the 100 rod 11. An angular spring detent 26 is fixed by a screw 27 to the inner or left-hand face of the part 23 and extends along over the top 105

of the rack 19, its free end being V-shaped as indicated at 28 to fit in the space between the teeth of the rack 19 and engage with said teeth to maintain the gage 23 in set or adjusted relationship with its support 17. 5 The spring detent 26 is self-acting and is in effect an automatically operating holding device. There are six interdental spaces in the rack 19, affording six adjustments of the 10 gage in respect to its support, these spaces being a letter space distance apart and thus providing for a denominational adjustment of the gage. To adjust or feed the gage in this manner, means controlled by a finger 15 piece or key are provided, said means comprising a gear element or segment 29 formed with an integral handle or stem 30 that is provided with a knob, finger piece or key 31. The gear segment is arranged at the 20 rear face of the disk 21 on which it is supported, said disk being provided with a bearing opening 32 which receives a hub 33 of a bearing member or circular cap 34 arranged at the front of the part 21. The hub 33 is threaded to receive the shank of a 25 headed screw 35 which secures the cap 34 in place, the head of said screw preventing displacement of the gear segment 29. This gear segment co-operates with the forward 30 portion of the rack 19 between the spring detent 26 and the part 21, the detent being narrower than the full width of the rack 19. Said detent has the additional function of assisting to hold the part 22 35 up in proper relationship with the slide, support or carrier 17. Confined between the front face of the part 21 and the cap 34 is a circular scale plate or indicating device 36 protected by a transparent facing 37 of celluloid or the like. The scale 40 plate or circular scale may be provided with two sets of indicating marks as shown in Figs. 1 and 3 and is adjustable to bring either set of indicating marks into working 45 position, that is, in position to co-operate with the handle 30 which acts as a pointer or indicator. The scale shown in working position in the drawing is intended for use where numbers are to be punctuated by 50 commas and runs from units ("U") to ten thousands ("TT"), while the lower scale which is out of use omits punctuation marks and runs to hundreds of thousands ("HT"). A pin 38 extending through the part 21 55 operates at its rear with the segment 29 and handle 30 to act as a stop, while at its front side said pin anchors the scale plate 36, passing through one of two openings 39 and 40 in said scale plate. When the hole 39 60 is engaged by the pin 38 the scale or set of indicating marks employing punctuation is used. In order to make use of the under scale it is necessary to loosen the screw and remove the cap so that the scale plate may 65 be disengaged from the pin 38 and turned

and adjusted to bring the hole 40 into engagement therewith.

The present invention may be employed in writing work forms of the sort illustrated and after the manner explained at length in my prior application aforesaid; that is, it may be used to facilitate the writing in figures of the amounts on checks, beginning close to the dollar sign in each instance whatever the amount, while these amounts are reproduced in a column on an underlying record sheet in proper denominational positions by the aid of the usual tabulating mechanism. Of course, other uses of the present invention will suggest themselves to those skilled in the art, but the work specified may be taken as an illustration. The record sheet (not shown) is introduced from the rear side of the machine and passed around the platen and up under the rolls 10. The bill sheet or check, indicated at P by dotted lines, is "front-fed" or introduced at the front side of the platen over the rod 11 and with its left-hand edge in contact with the right-hand vertical face of the side gage 90 stop or guide proper 23. Assuming that the contrivance as a whole has been properly adjusted lengthwise of the platen along the rod 11 it is fixed or set by tightening the thumb screw 18. It may be said here that the contrivance is readily adjusted by pulling it away from the rod 9 to the dotted line position in Fig. 2 after which the set screw may be loosened and the contrivance slid to desired position before re-tightening. The 95 spring 14 will restore the hook 24 to engagement with the rod 9 and it will be observed that this spring has a double function as after such restoration its tension will be exerted to communicate pressure to the pressure bail, increasing the pressure of the rolls 10 against the platen. Let it further be assumed that the amount to be written is ten thousand dollars, the knob or button 31 is swung to the left as far as it will go or until the stop pin 38 arrests the gear segment as shown in Fig. 4, at which time the stem or handle portion 30 will be opposite the "TT" indicating mark as shown in Figs. 1 and 3. The movement of the finger piece or key 110 causes the connections or rack and gear elements 19 and 29 to co-operate to move the device 20 on its support 19, the gage proper 23 traveling toward the left lengthwise of the platen until the parts are arrested by the 115 stop pin 38 which has the additional function of preventing the device 20 from being disconnected from its support. The check P is then introduced, being properly positioned lengthwise of the platen, by means of the gage 23 and the various printing and spacing operations described in detail in said prior application are carried out, after which the check is removed and the operations repeated with a new check. If the new 120 125 130

check is for a smaller sum, say, for a thousand dollars, the finger piece 31 is moved to the right until the stem 30 is brought opposite the "T" mark, causing the gage 23 to be moved a letter space distance toward the right. If the next amount is for a hundred dollars, say, the gage is adjusted two further spaces to the right. If it be assumed that the next check is for units of dollars, say, 10 eight, the finger piece or key 31 is swung to the extreme right operating through the connections 29, 19 to move the gage 23 from left to right or until the dotted line position indicated in Figs. 3 and 4 is arrived at. 15 This is the limit of movement toward the right as determined by contact of the handle portion 30 with the stop pin 38.

It will be observed that the key controlled gage 23 is settable progressively or step-by-step at letter space intervals lengthwise of the platen so as to position said gage denominational without affecting or disturbing the setting of the support 17 which remains in the same set position for all of 25 the six denominational settings of which the gage 23 is capable. Further it will be seen that the contrivance as a whole may be set in any desired position along the platen and that when set in this desired position the 30 single gage which replaces the set of gages in my prior construction may be independently set in any one of six denominational positions, the connections or setting means 31, 30, 29, 19 being independent of the setting or fixing means 18 for the contrivance as a whole. While the gage or stop device is adjustable step-by-step it may be moved rapidly from one extreme to the other or to any intermediate position, the detent spring 40 clicking over the teeth of the rack 19 during such movement. Said rack when once set remains fixed while the coöperating gear segment 29 moves bodily or as a whole as well as receives a rotary movement when its 45 key is actuated.

Various changes may be made without departing from my invention.

What I claim as new and desire to secure by Letters Patent, is:—

50 1. In a typewriting machine, the combination of a platen, a denominational side gage, mechanism which when operated causes a denominational feeding movement of said gage lengthwise of the platen, and 55 an automatically operating holding device which holds the side gage in set position after it has been fed.

2. In a typewriting machine, the combination of a platen, and a side gage contrivance adjustable as a whole lengthwise of the platen, said contrivance comprising a side gage proper and key operated means for feeding said side gage proper step-by-step through predetermined regular distances 60 lengthwise of the platen without chang-

ing the location of said contrivance as a whole.

3. In a typewriting machine, the combination of a platen, and a denominational side gage contrivance settable at desired 70 points along the platen, said contrivance comprising a key controlled side gage adjustable in a plurality of different positions for each point at which the contrivance as a whole may be set.

4. In a typewriting machine, the combination of a platen, a side gage adjustable step by step by the operation of a single key through regular predetermined distances lengthwise of the platen, and devices comprising 80 an automatically operating detent for holding the side gage in adjusted positions.

5. In a typewriting machine, the combination of a platen, and a denominational side gage contrivance comprising a single 85 side gage movable step by step through predetermined distances along the platen through the operation of a finger piece and detent devices for said gage.

90 6. In a typewriting machine, the combination of a platen, a single side gage, means controlled by a finger piece for progressively setting said gage at predetermined intervals along the platen and automatically operating holding means for holding said gage in set positions.

7. In a typewriting machine, the combination of a platen, a single denominational side gage progressively adjustable at predetermined 100 points a letter space distance apart, and means operating automatically to hold said gage in adjusted positions.

8. In a typewriting machine, the combination of a platen, a platen carrier, a denominational side gage contrivance supported from said platen carrier and movable as a whole lengthwise of said platen, and means for positively fixing the position of said contrivance in adjusted positions, said contrivance comprising a gage settable independently of said means.

9. In a typewriting machine, the combination of a platen, a platen carrier, a denominational side gage contrivance mounted 115 on said platen carrier, and means for positively fixing said contrivance in adjusted positions lengthwise of said platen, said contrivance comprising a gage, means independent of said first recited means for moving 120 said gage step-by-step lengthwise of the platen, and detent devices for maintaining said gage set in adjusted positions.

10. In a typewriting machine, the combination of a platen, a platen carrier, a slide, 125 means for fixing the position of said slide, a side gage supported by said slide, and rack and gear connections between said slide and said side gage.

11. In a typewriting machine, the combi- 130

1. In a typewriting machine, the combination of a platen, a platen carrier, a slide, means for fixing the position of said slide, a side gage slidably mounted on said slide, and stop devices for limiting the movements 5 of said side gage.
2. In a typewriting machine, the combination of a platen, a platen carrier, a slide, means for fixing the position of said slide, a side gage slidably mounted on said slide, a side gage supported by said slide, rack and gear connections between said slide and said 10 side gage, and a finger piece connected to operate said connections.
3. In a typewriting machine, the combination of a platen, a platen carrier, a slide, means for fixing the position of said slide, a side gage slidably mounted on said slide, a side gage supported by said slide, rack and gear connections between said slide and said 15 side gage, and a finger piece connected to operate said connections, and stop devices to limit the movements of said finger piece.
4. In a typewriting machine, the combination of a platen, a platen carrier, a slide, means for fixing the position of said slide, a side gage slidably mounted on said slide, and detent devices effective only to maintain said side gage in adjusted positions at letter space 20 intervals.
5. In a typewriting machine, the combination of a platen, a platen carrier, a slide, means for fixing the position of said slide, a side gage slidably mounted on said slide, stop devices for limiting the movements of 25 said side gage, and detent devices for maintaining said side gage in adjusted positions.
6. In a typewriting machine, the combination of a platen, a platen carrier, a slide, means for fixing the position of said slide, a side gage supported by said slide, rack and gear connections between said slide and said side gage, and a detent spring on said side gage 30 co-operative with certain of said rack and gear connections to maintain said side gage in adjusted positions.
7. In a typewriting machine, the combination of a platen, a platen carrier, a rod on said carrier extending lengthwise of the platen, a slide on said rod and provided 35 with a rack, a thumb screw for fixing the position of said slide, and a side gage device comprising a side gage proper, a frame partly surrounding said slide, and a gear segment provided with a finger piece and meshing with said rack.
8. In a typewriting machine, the combination of a platen, a platen carriage, a gage carrier, a side gage mounted on said carrier, rack and gear connections between said side 40 gage and said carrier, and detent devices co-operative with certain of said rack and gear connections.
9. In a typewriting machine, the combination of a platen, a platen carrier, a support 45 adjustable lengthwise of said carrier,
- means for fixing said support, a side gage mounted on said support, and hand controlled rack and gear connections between said support and said gage.
10. In a typewriting machine, the combination of a platen, a platen carrier, a support adjustable lengthwise of said carrier, means for fixing said support, a side gage mounted on said support, hand controlled rack and gear connections between said support and said gage, and a detent spring fixed to said gage and co-operative with said rack.
11. In a typewriting machine, the combination of a platen, a platen carrier, a support adjustable lengthwise of said carrier, means for fixing said support, a side gage mounted on said support, rack and gear connections between said support and said slide, a finger piece for controlling said rack and gear connections, and a stop on said gage co-operative with said finger piece.
12. In a typewriting machine, the combination of a platen, a rod extending lengthwise of the platen, a slide on said rod and provided with a rack, a thumb screw for fixing the position of said slide, a side gage device comprising a side gage proper, a frame partly surrounding said slide, a gear segment provided with a finger piece and meshing with said rack, and a circular scale with which said finger piece co-operates.
13. In a typewriting machine, the combination of a platen, a rod or bar extending lengthwise of the platen, a supporting device settable on said rod and provided with a rack, a side gage element slideable on said support, and a gear segment pivoted on said side gage element and provided with a finger piece, said segment meshing with said rack.
14. In a typewriting machine, the combination of a platen, a support, a paper stop, rack and gear elements connecting said stop with said support, and a key operating on said elements to move said paper stop on its support step-by-step.
15. In a typewriting machine, the combination of a platen, a rack, means for fixing the same in adjusted positions lengthwise of the platen, a paper stop, a gear pivotally connected with said paper stop and meshing with said rack, and a key operative on said gear to move said paper stop step-by-step.
16. In a typewriting machine, the combination of a platen, a support, a side gage, and rack and gear elements connecting said side gage with said support, the gear element being pivoted on said side gage and provided with a finger piece.
17. In a typewriting machine, the combination of a platen, a support, a side gage, rack and gear elements connecting said side gage with said support, the gear element being pivoted on said side gage and pro-

vided with a finger piece, and indicating devices for said side gage, said devices comprising a circular scale for which said finger piece serves as a pointer.

5 28. In a typewriting machine, the combination of a platen, a support, a side gage, rack and gear elements connecting said side gage with said support, the gear element being pivoted on said side gage and provided 10 with a finger piece, and indicating devices for said side gage, said indicating devices comprising a circular scale provided with two sets of indicating marks, said scale being adjustable to bring either set into use 15 to coöperate with said finger piece which serves as a pointer.

29. In a typewriting machine, the combination of a platen, a side gage device comprising a side gage proper, and controlling 20 devices comprising a rotary finger piece operative to move said side gage denominational lengthwise of the platen.

30. In a typewriting machine, the combination of a carriage, a platen carrier, a 25 frame comprising parallel arms pivotally supported on said platen carrier, a rod or shaft pivoted on said arms, a side gage contrivance supported on said rod or shaft, and a spring tending to turn said rod to bring 30 said gage to operative position, said spring also tending to turn said frame about its pivotal axis.

31. In a typewriting machine, the combination of a platen, a platen carrier, a pressure bail pivotally supported on said platen carrier and coöoperative with the platen, a rod or shaft supported on said pressure bail, a side gage contrivance on said rod or shaft, and a coiled spring connected to said rod 40 or shaft and tending to turn it to bring said contrivance to operative position, said spring also operating to apply pressure to said bail.

32. In a typewriting machine, the combination of a platen, a platen carrier, a pressure bail pivoted on said platen carrier and comprising a rod provided with pressure rolls coöoperative with the platen, a second rod mounted on said bail, a side gage contrivance on said second rod, and a spring 50 connected to said second rod and tending to maintain said contrivance in engagement

with said first named rod, said spring also applying pressure to said rolls.

33. In a front-strike typewriting machine, 55 the combination of a platen, a platen carrier comprising a front bar, a pressure bail mounted on said bar and comprising a rod provided with pressure rolls coöoperative with the front face of the platen above the 60 printing line, a second rod or bar pivotally supported on said bail, a side gage contrivance carried by said second rod and comprising a side gage proper extending from said second rod to said first named rod, and a 65 spring for maintaining said side gage proper in engagement with said first named rod, said spring also applying pressure to said rolls.

34. In a typewriting machine, the combination of a platen, a rod or shaft extending 70 lengthwise of the platen, a second rod or shaft parallel to the first rod, spring means tending constantly to turn said second rod on its axis, a side gage contrivance mounted on said second rod and comprising a side 75 gage proper extending to and contacting with the first rod, said contrivance also comprising a support adjustably fixed to said second rod, said first rod being capable of rotary movement to withdraw said side 80 gage proper from contact with said first rod so as to afford ready adjustment of said support along said second rod.

35. In a front-strike typewriting machine, 85 the combination of a platen, a platen carrier, a pressure bail supported on said carrier and coöoperative with the platen above the printing line, a side gage contrivance rotatably supported on said pressure bail at the front side of the platen and provided 90 with a side gage extending toward the platen and coöoperative with a work sheet introduced at the front side of the platen, and means for adjusting said side gage proper step-by-step without disturbing the 95 location of said contrivance as a whole.

Signed at the borough of Manhattan, city of New York, in the county of New York, and State of New York, this 23rd day of November, A. D. 1915.

ARTHUR W. SMITH.
